(57) **CLAIM**

The ornamental design for tableware set, as shown.

DESCRIPTION

FIG. 1 is a perspective view of a coffeepot portion of the tableware set showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a salad bowl of the tableware set;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a milk jug of the tableware set;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a perspective view of a dish of the tableware set;

FIG. 23 is a front view thereof;

FIG. 24 is a rear view thereof;

FIG. 25 is a left side view thereof;

FIG. 26 is a right side view thereof;

FIG. 27 is a top view thereof;

FIG. 28 is a bottom view thereof;

FIG. 29 is a perspective view of a soup plate of the tableware set;

FIG. 30 is a front view thereof;

FIG. 31 is a rear view thereof;

FIG. 32 is a left side view thereof;
FIG. 33 is a right side view thereof;
FIG. 34 is a top view thereof;
FIG. 35 is a bottom view thereof;
FIG. 36 is a perspective view of a plate of the tableware set;
FIG. 37 is a front view thereof;
FIG. 38 is a rear view thereof;
FIG. 39 is a left side view thereof;
FIG. 40 is a right side view thereof;
FIG. 41 is a top view thereof;
FIG. 42 is a bottom view thereof;
FIG. 43 is a perspective view of a cup of the tableware set;
FIG. 44 is a front view thereof;
FIG. 45 is a rear view thereof;
FIG. 46 is a left side view thereof;
FIG. 47 is a right side view thereof;
FIG. 48 is a top view thereof;
FIG. 49 is a bottom view thereof;
FIG. 50 is a perspective view of a teapot of the tableware set;
FIG. 51 is a front view thereof;
FIG. 52 is a rear view thereof;
FIG. 53 is a left side view thereof;

FIG. 54 is a right side view thereof;
FIG. 55 is a top view thereof;
FIG. 56 is a bottom view thereof;
FIG. 57 is a perspective view of a sugar bowl of the tableware set;
FIG. 58 is a front view thereof;
FIG. 59 is a rear view thereof;
FIG. 60 is a left side view thereof;
FIG. 61 is a right side view thereof;
FIG. 62 is a top view thereof;
FIG. 63 is a bottom view thereof;
FIG. 64 is a perspective view of a soup-tureen of the tableware set;
FIG. 65 is a front view thereof;
FIG. 66 is a rear view thereof;
FIG. 67 is a left side view thereof;
FIG. 68 is a right side view thereof;
FIG. 69 is a top view thereof;
FIG. 70 is a bottom view thereof; and,
FIG. 71 is a view of the tableware set shown together showing my new design.
